UNITED STATES PATENT OFFICE.

ALEXANDER H. WOOD, OF KILDAV, KENTUCKY, ASSIGNOR TO WOOD EQUIPMENT COMPANY, OF CHICAGO, ILLINOIS, A CORPORATION OF ILLINOIS.

CAR-TIPPLE.

1,299,527.

Specification of Letters Patent.

Patented Apr. 8, 1919.

Application filed June 21, 1917. Serial No. 176,126.

To all whom it may concern:

Be it known that I, ALEXANDER H. WOOD, a citizen of the United States, residing in Kildav, in the county of Harlan and State 5 of Kentucky, have invented new and useful Improvements in Car-Tipples, of which the following is a specification.

This invention relates to improvements in car tipples more especially of the type designed to receive mine cars loaded with coal, 10 ore or other material, and to overturn them to discharge their contents. The invention contemplates a car tipple mounted to rotate on a horizontal axis with rails in its bottom 15 to support a car, the general tipple structure being made in accordance with well known principles, and this invention relates more particularly to the means for rotating the tipple and for restoring it to its normal 20 position.

An apparatus embodying the principles of the invention comprises in general terms the rotating structure designed to receive a car and preferably made in the general form of 25 an open-ended, horizontal cylinder, around which there is wound a rope or cable with the two ends of the latter connected to the piston rods of a cylinder or cylinders by means of which a pull may be imparted to 30 the rope or cable from either end to rotate the tipple cylinder.

An apparatus embodying the principles of the invention is illustrated in the accompanying drawings in which:

35 Figure 1 is a view of the complete tipple and operating mechanism in end elevation.

Fig. 2 is a similar view showing a modified form of the operating mechanism.

Fig. 3 is a radial section through one of 40 the valves of the apparatus.

Fig. 4 is a radial section through the other valve of the apparatus.

As shown in said drawings in Figs. 1, 3 and 4, the car tipple is made in the general 45 form of a large horizontal cylindric structure, 10, resting on wheels, 11, and adapted to rotate about a substantially horizontal axis, the framing in the lower part of the cylinder supporting a pair of rails, 12, 50 adapted to receive a loaded car which is overturned by the rotation of the cylinder to empty its load. This part of the apparatus is made in accordance with well known principles and its particular design or construction is not involved in this invention 55

except that the cylinder is made in such form as to provide at some place in its length a circular section in the form of a drum about which is wound a rope or cable, 24.

In any convenient location adjacent to 60 that side of the cylinder 10 toward which its upper part rotates in the dumping operation is located a cylinder, 30, in which is a movable piston, 31, with a piston rod, 32, attached to one end of the cable 24; the latter 65 passing over a sheave, 33. The other end of the cable is led around a similar sheave, 40, and attached in the same manner to the end of a piston rod connected to the piston in a cylinder, 44; and the two cylinders are 70 connected by suitable piping to a source of fluid pressure, preferably pneumatic, here shown as an air pressure tank, 50, although if desired the apparatus may be worked equally effectively with steam, and in such 75 case the air tank 50 would be replaced by a steam boiler.

From the pressure tank or storage tank 50 a pipe, 55, is connected to one of the ports of a 4-way valve, 56, and the opposite port, 80 57, of this valve opens into the atmosphere. One of the intermediate ports is connected through a pipe, 60, to the pressure side of the cylinder 30, and the remaining port is connected through a pipe, 63, to the pressure 85 side of the cylinder 44. In addition there is interposed in the pipe 63, between the valve 56 and the cylinder 44 a 3-way valve, 70, one of the ports of which is open to the atmosphere. 90

In the operation of the device, after a loaded car, or a trip of two or more cars, has entered the tipple, the 4-way valve 56 is adjusted to admit air or steam into the cylinder 30 and to permit it to escape from the 95 cylinder 44 whereby the pull on the rope or valve 24 imparted by the cylinder 30 acts to rotate the tipple and overturn the cars; this rotating operation being permitted by allowing the air or steam to escape from the cylinder 44 through the pipe 63 and the outlets of the two valves 56 and 70, while at the same time the cable is kept tight and the rotation is checked and controlled by adjusting the valve 70 to restrict the outlet from the pipe 100 63 to any desired extent and retard the escape of air from the cylinder 44, which latter acts as a brake in the overturning operation. When it is desired to return the cars 105 to their upright position the valve 56 is ad- 110

justed into its opposite position, as shown in Fig. 3, to permit the escape of pressure from the cylinder 30 and to utilize whatever pressure may remain in the cylinder 44 after serving to cushion the movement of the tipple; such additional air or steam as may be necessary being supplied to the cylinder 44 from the pressure tank 50 to return the tipple to its normal position. This additional air is admitted to the cylinder through the pipes 55 and 63 and the valve 70, which latter may be adjusted to permit a straight passage of air through it, either restricted or unrestricted, or, if desirable, it may be adjusted to restrict the passage of air through it and also to permit some of the air to escape through its third port into the atmosphere, as shown in Fig. 4, so as to avoid too great pressure in the cylinder 44 and a too violent return of the tipple to its original position, this adjustment of the valve being called "splitting" the air and allowing part of it to enter the cylinder and part of it to escape.

If the valve 70 is adjusted into such a position as to permit an unobstructed discharge of fluid straight through it and no escape through its outlet port it is evident that it will have no effect whatever in the operation of the mechanism, and this valve might be omitted from the mechanism without seriously impairing the effectiveness of its operation; but the addition of this valve is believed to be desirable as it permits of restricting the outlet from the cylinder 44 independently of the position of the 4-way valve, and it also permits of restricting the admission of fluid to the cylinder 44 and of "splitting the air" and allowing some of it to escape, likewise independently of the position of the 4-way valve.

The rotation of the tipple structure or cylinder 10 in either direction is limited by a projecting stop or lug, 75, which engages against one of two posts, 76 and 77, according to the direction of rotation; the operative movement of the tipple being counter

clockwise, as viewed in Fig. 1, to overturn the car or cars and discharge their load down into a chute, 80, below the tipple, and the return movement being in the opposite direction.

In Fig. 2 is shown a form of the apparatus substantially similar to that above described, with a rotary tipple structure, 90, and a rope or cable, 91, wound about it to impart movement thereto, but the ends of the cable instead of connecting to two pneumatic or hydraulic cylinders, are connected to the free ends of two piston rods which are joined to a single piston, 98, in a double-acting cylinder, 99. The two ends of the cylinder are connected through a 4-way valve, 100, and a 3-way valve, 101, similar in all respects to those above described, with a storage tank or steam boiler, 102, and the operation of the mechanism is exactly the same as that above described except that the operating fluid is admitted to one end of the cylinder 99 in the overturning movement and exhausted from the other end; and to restore the tipple the piston is driven in the opposite direction by reversing the direction of admission and exhaust, as will be readily understood.

A pulley 110, supporting a weight 112, is hung on the rope to take up slack.

I claim as my invention:

An operating mechanism for rotary tipples and the like, comprising a source of fluid pressure, two pressure cylinders, with a piston in each, the two pistons being connected by a rope, a 4-way valve connecting the source of fluid pressure with the two cylinders and with an outlet whereby fluid may be diverted to either cylinder and exhausted from the other cylinder, and a 3-way valve between the 4-way valve and one of the cylinders.

In witness whereof I have hereunto subscribed my name this 15th day of June, 1917.

ALEXANDER H. WOOD.
